UNITED STATES PATENT OFFICE.

BERTHOLD SCHNEIDER, OF BERLIN, GERMANY.

FARE INDICATOR AND REGISTER FOR VEHICLES.

No. 902,332.

Specification of Letters Patent.

Patented Oct. 27, 1908.

Application filed September 14, 1906. Serial No. 334,657.

To all whom it may concern:

Be it known that I, BERTHOLD SCHNEIDER, engineer, citizen of the German Empire, residing at Berlin, have invented certain new and useful Improvements in Fare Indicators and Registers for Vehicles, of which the following is a specification.

This invention relates to an attachment for use in connection with vehicles provided with fare indicators wherein the registering mechanism of the fare indicator is adjusted to indicate the various fares, to "cash" and to "unoccupied" by means of a flag and not by a separate adjusting lever or key to indicate whether the vehicle is occupied or unoccupied; is designed as an improvement upon the form of attachment set forth in Letters Patent No. 777,697 granted to me December 20, 1904 and the primary object thereof is to so set up the attachment with respect to the adjusting shaft of the registering mechanism that the flag is positively connected with said shaft, as well as enabling the flag to be attached to any suitable point upon the fare indicator; furthermore it enables the flag to be arranged at such a point as to prevent the driver's seat from interfering with the flag when rotating it through a complete revolution, that is to say it is not necessary to provide a special space for the movement of the flag.

A further object of the invention is to provide an attachment for fare indicators in a manner as hereinafter set forth and so set up the attachment with respect to the adjusting shaft of the registering mechanism as to enable the flag to project laterally from the casing of the fare indicator so that the flag staff is rotated by means of the flag, not around its end but around its axis. Under such circumstances the flag staff can be dispensed with as the flag staff can be employed as a flag shaft.

Referring to the drawings which form a part of this specification:—Figure 1 is a front view showing the attachment in accordance with this invention. Fig. 2 is a top plan view showing the flag staff projecting laterally from the casing and which is adapted to be rotated around its axis in such a manner that the adjustment is effected by its axial rotation, and Fig. 3 is a view similar to that of Fig. 1 of a modified construction, in which one end of the flag staff is keyed on a flag shaft and in which the flag staff has to be ro-

tated through a complete revolution around this end for the purpose of adjustment.

In connection with the use of the construction in accordance with this invention, it will be pointed out that in certain countries cabs and the like are hired at different rates or fares, fare 1 for one or two persons, fare 2 for three or four persons, and fare 3 for five persons. If a passenger leaves the cab, the driver has to place the indicator or taximeter to "cash" in order to show the passenger what amount he has to pay, and then the driver has to adjust the indicator to indicate "unoccupied" so that when such indication is exposed, it will show to others that the cab can be hired. Under such conditions it necessitates the employment of means to alter the positions of the fare registers between the fares 1 to 3, because it might happen that two persons are driving and a third entering, therefore the register must be adjusted so as to change the indication from fare 1 to fare 2 and so on.

Referring to Figs. 1 and 2 in detail, *a* denotes a bed plate carrying suitable bearings in which is journaled a register setting shaft *b* having rigidly secured thereto a disk *c*, a ratchet wheel *d* and a bevel wheel *s*. The periphery of the disk *c* is provided with recesses *h*, the number of which corresponds with that of the possible indications as, for instance, fares 1 to 3, "cash" and "unoccupied", and when the adjusting shaft *b* is rotated, the said recesses *h* receive in the usual manner a detent *f* carried by a spring blade *g*. To prevent the apparatus from being accidentally rotated in a backward direction, as for instance from "cash" to "unoccupied" or from "cash" to "fare", there is provided a spring actuated pawl *i* which engages with the ratchet wheel *d*, the latter being provided with teeth on a part of its periphery. The pawl *i* rests upon the smooth part of the periphery of the wheel *d* when the apparatus is adjusted to the different rates of fare, that is to say from fare 1 to fare 3, and it is consequently possible to rotate the apparatus forwards and backwards within the range of the fares. The disk *c* is provided with a carrier *k* which, when the apparatus is adjusted to indicate fare, releases a bolt *n* which by means of a lever *m* suitably sets the registering mechanism which is not shown in the drawing.

The construction just set forth and de-

scribed with respect to the ratchet wheel and the means for actuating the registering mechanism is well known and no claim is made therefor. The construction, however, has 5 been briefly explained for the sake of completeness and to facilitate the understanding of the application of the attachment in accordance with this invention.

The staff *q* that carries the flag is mounted 10 in a bearing *u* attached to the bed plate *a* and is secured in a set position by means of the collars *v* fixed to the staff *q*. One end of the staff *q* carries a bevel wheel *t* which engages with a bevel wheel *s* mounted on the adjusting 15 shaft *b*.

If the flag is rotated from the position shown in Fig. 1 forwards as viewed from the interior of the vehicle in the direction of the arrow 4 (assuming the fare indicator to be 20 fixed to the right side of the vehicle) the bevel wheel *t* will actuate the bevel wheel *s* together with the adjusting shaft *b* and the disk *c* and ratchet wheel *d* will thus be actuated in the direction of the arrow 3. Therefore, 25 by means of the ratchet mechanism referred to the indications can be adjusted both forwardly and rearwardly by means of the flag for the fares from 1 to 3; the apparatus, however, cannot be turned backwards from 30 "cash" to "fare", except by first adjusting the apparatus to "unoccupied".

In the construction shown in Fig. 3, the flag staff is mounted on a special shaft *z* which carries a spur wheel *y* which engages 35 with a spur wheel *x* keyed upon the adjusting shaft *b*. In the construction shown in Fig. 3, it is therefore necessary to rotate the flag staff *q* around one of its ends in the direction of the arrow 2, whereby both the flag shaft *z* and the shaft *b* which is connected therewith 40 through the spur wheels *x* and *y* are so rotated as to enable the ratchet wheel *c* to effect the desired indications.

Owing to the modifying of the intermediate 45 connections between the staff and shaft, the flag is positively connected with the adjusting shaft and the flag can be attached to any suitable place on the indicator. It may, for instance, be arranged so high that the 50 driver's seat is not in the way thereof when the flag staff is rotated through a complete revolution, that is to say it is not necessary to provide a special space for the movement of the flag, or the flag may be so arranged as to 55 project laterally from the casing of the indicator in such a manner that the flag staff is

rotated by means of the flag, not around its end but around its longitudinal axis as a center. Under such circumstances, moreover, the flag shaft can be dispensed with as the flag 60 staff can be employed as the flag shaft.

I claim—

1. A fare indicator comprising a register setting shaft, a flag staff movable about an axis displaced relatively to said shaft and a 65 gear connection between the staff and the shaft for operating the latter from the staff and allowing of the rotation of the staff through a complete revolution.

2. A fare indicator comprising a register 70 setting shaft for the controlling mechanism, a flag staff, a second shaft to which the flag staff is connected, and a gear connection between the last-mentioned shaft and the register setting shaft, said operative connection 75 adapted to impart movement to the register setting shaft when the flag staff is shifted.

3. A fare indicator comprising a register setting shaft, a flag staff, a second shaft to which the flag staff is connected, and means 80 carried by the last mentioned shaft and adapted to engage with the register setting shaft for imparting movement to the latter when the flag staff is shifted.

4. A fare indicator comprising a register 85 setting shaft, a flag staff adjustable about a different axis relatively to said shaft, and mechanism for positively connecting the flag staff with the adjusting shaft, thereby imparting movement to the latter when the flag 90 staff is shifted.

5. A fare indicator comprising a register setting shaft, a flag or signal staff rotatable about its longitudinal axis as a center, and an operative connection between said staff and 95 shaft for transmitting motion between them and permitting a complete revolution of the staff.

6. A fare indicator comprising a register setting shaft, a signal staff rotatable about an 100 axis arranged in angular relation to said shaft, and cooperating gears fixed to said shaft and staff for transmitting motion between them.

In testimony whereof I have hereunto set 105 my hand in presence of two subscribing witnesses.

BERTHOLD SCHNEIDER.
